UNITED STATES PATENT OFFICE.

JACOB V. ROWLETT, OF RICHMOND, INDIANA.

FOOT-PLATE FOR SKATES.

SPECIFICATION forming part of Letters Patent No. 313,624, dated March 10, 1885.

Application filed August 29, 1884. (No mode¹.)

To all whom it may concern:

Be it known that I, JACOB V. ROWLETT, of Richmond, in the county of Wayne, and the State of Indiana, have invented certain Im-
5 provements in Foot-Plates for Skates, of which the following is a specification.

My invention relates to a new mode of constructing a metal foot-plate for skates, in which I use a longitudinal stay or brace attached
10 thereto in such manner as to form a truss, by which means I attain both cheapness and lightness in construction, all as hereinafter fully described, and set forth in the specification and claims.

15 Figure 1 is a perspective view. Fig. 2 is a longitudinal vertical section.

A is the foot-plate; B, the stay or brace; C, the vertical support placed between the foot-plate and stay, and forming a complete truss, 20 and held in place by means of the rivet or any other suitable means. The stay or brace is attached to the foot-plate by means of the rivets d e, or any other suitable means. The stay or brace may be used with or without the strut or support C interposed between it and the 25 foot-plate A, as may be desired, and the vertical support C may be constructed in any suitable form.

Having thus fully described my invention, what I claim, and desire to secure by Letters 30 Patent, is—

1. In a foot-plate for roller-skates, a stay or brace underlying the upwardly-curved instep portion and attached to the plate at its ends, substantially as specified.
2. In a foot-plate for roller-skates, a stay or brace underlying the upwardly-curved instep portion, in combination with the strut or post interposed between said stay and the plate, substantially as specified.

JACOB V. ROWLETT.
